UNITED STATES PATENT OFFICE

148,326

DESIGN FOR A RADIO PHONOGRAPH CABINET

Joseph D. Portanova, Los Angeles, Calif., assignor
to Hoffman Radio Corporation, Los Angeles,
Calif., a corporation of California

Application September 9, 1946, Serial No. 133,189

Term of patent 3½ years

(Cl. D56—4)

To all whom it may concern:

Be it known that I, Joseph D. Portanova, a citizen of the United States, residing at Los Angeles, California, have invented a new, original, and ornamental Design for a Radio Phonograph Cabinet, of which the following is a specification, reference being had to the accompanying drawings, forming a part thereof, in which:

Fig. 1 is a front perspective view of a radio phonograph cabinet embodying my new design,

Fig. 2 is a side elevational view thereof,

Fig. 3 is a top plan view thereof, and

Fig. 4 is a view similar to Figure 1 but illustrating the appearance with doors and cover open.

The characteristic features of the design are shown in solid lines in the drawing.

I claim:

The ornamental design for a radio phonograph cabinet, substantially as shown and described.

JOSEPH D. PORTANOVA.
